Fig. 18

FIG. 1 is a side elevational view of a reed for a reed switch assembly;

FIG. 2 is a bottom plan view thereof;

FIG. 3 is an end view thereof;

FIG. 4 is a side elevational view of a modified form of the reed described in FIG. 1 showing our new design;

FIG. 5 is a bottom plan view thereof;

FIG. 6 is an end view thereof;

FIG. 7 is a side elevational view of a modified form of the reed described in FIG. 1 showing our new design;

FIG. 8 is a bottom plan view thereof;

FIG. 9 is an end view thereof;

FIG. 10 is a side elevational view of a modified form of the reed described in FIG. 1 showing our new design;

FIG. 11 is a bottom plan view thereof;

FIG. 12 is an end view thereof;

FIG. 13 is a side elevational view of a modified form of the reed described in FIG. 1 showing our new design;

FIG. 14 is a bottom plan view thereof;

FIG. 15 is an end view thereof;

FIG. 16 is a side elevational view of a modified form of the reed described in FIG. 1 showing our new design;

FIG. 17 is a bottom plan view thereof; and

FIG. 18 is an end view thereof.

The end opposite to the ends shown in FIGS. 3, 6, 9, 12, 15 and 18 are identical with these figures respectively. The ends are shown fragmentary on one end and broken away at the other end to show indeterminate length. The sides opposite to the sides shown in FIGS. 1, 4, 7, 10, 13 and 16 are mirror images of these figures respectively. The top plan views opposite to the bottom plan views shown in FIGS. 2, 5, 8, 11, 14 and 17 are identical with these views.

We claim:

The ornamental design for a reed for a reed switch assembly, as shown and described.
